NEEDLE-THREADER

Daniel H. Chason, Elizabeth, N. J., assignor to
The Singer Manufacturing Company, Elizabeth, N. J., a corporation of New Jersey

Application March 22, 1935, Serial No. 12,354

4 Claims. (Cl. 223—99)

This invention relates to sewing machine needle-threaders and has for an object to provide a needle-threader which will handle silk as well as cotton threads of the various sizes and textures customarily used with sewing machines, without splitting, fraying or being caught by the fibres of such threads. Another object of the invention is to provide a needle-threader which may be readily manipulated by the operator with materially decreased danger of catching in the eye of the sewing machine needle.

A further object of the invention is to provide a needle-threader the hook of which is so constructed as to minimize the dangers of catching and splitting the fibres of the thread—particularly silk thread—and of being broken or deformed under normal operating conditions.

With the above and other objects in view, as will hereinafter appear, the invention comprises the devices, combinations and arrangements of parts hereinafter set forth and illustrated in the accompanying drawing of a preferred embodiment of the invention, from which the several features of the invention and the advantages attained thereby will be readily understood by those skilled in the art.

A feature of the invention is the formation of the threader-hook from piano wire and the provision of a bent portion forming a blunt nose at the free end of the hook-forming portion of the wire.

Another feature of the invention is the formation of the threader-hook from spring wire; the hook being shaped to provide an outwardly flaring mouth and a restricted thread-receiving throat which is narrower than the normal or uncompressed diameter of a conventional sewing machine thread, so that the thread may be passed laterally of itself into the hook and then released without danger that it will slip out of the hook prior to withdrawal of the hook from the eye of the sewing machine needle.

In the accompanying drawing, Fig. 1 is a side elevation of a combined needle-threader and seam-ripper embodying the invention. Fig. 2 is a side elevation of the threader with the front guard-plate removed. Fig. 3 is a top plan view of the threader including the guard-plates. Fig. 4 is a similar view with the guard-plates removed. Figs. 5 and 6 are, respectively, enlarged sections on the lines 5—5 and 6—6, Fig. 1. Fig. 7 is a disassembled perspective view of the guard-plates. Figs. 8 and 9 are, respectively, enlarged sections on the lines 8—8 and 9—9, Fig. 3. Fig. 10 is a side elevation of the threader inserted in the eye

of a sewing machine needle to illustrate the method of using the device. Fig. 11 is an enlarged side elevation of the threader-hook. Fig. 12 is a similar view of a modified form of the threader-hook. Fig. 13 is a fragmentary view of the threader-supporting shank showing the threader-positioning grooves, and Fig. 14 is a section on the line 14—14, Fig. 13.

1 represents a suitable handle such as disclosed in my copending application Serial No. 712,123, filed February 20, 1934. Pivotedly mounted at 2 and 3 in the handle 1 are the seam-ripping knife 4 and needle-threader 5, respectively, either of which may be swung about its pivot from closed to open position, as the blade of a pocket knife.

The needle-threader 5 comprises a flat supporting shank in the form of a bar 6 of rectangular cross-section reduced in thickness at its free end to form a flat face 7 and a positioning shoulder 8 for the shank 9 of the threader implement 20 which is preferably formed from a tough high-grade spring-steel wire, of circular section, such as piano wire. The diameter of the wire is preferably about 6 mils. The shank 9 is formed at its base end with a right-angularly-bent positioning portion 10 which is seated against the positioning shoulder 8 and in a groove 8' at the base of the shoulder 8 of the supporting shank 6. The horizontal shank portion 9 of the threader wire is seated in the positioning groove 9' in the 30 face 7 of the bar 6 and both the horizontal shank portion 9 and vertical base portion 10 of the wire are clamped to their seats by the head of the screw 11. The head of the screw 11 is thin and does not project beyond the plane of the 35 front face of the threader-supporting shank 6.

The threader wire shank 9 is bent upon itself at its free end to form the hook 12, Fig. 11, and the free end 13 of the hook-forming portion 12 of the wire is bent outwardly and back upon itself 40 to form a rounded blunt nose 14 defining with the shank 9 the outwardly flaring, smooth, thread-receiving mouth 15 which leads to the hook cavity 15^c through the restricted throat 15^x; the latter being narrower than the normal or uncompressed 45 diameter of a conventional sewing machine thread and preferably standing slightly open, say a distance of 2 mils. The maximum width of the hook-end of the threader is slightly less than the length of the eye of the smallest conventional 50 sewing machine needle, so that the hook may be freely inserted therein. The return-bent portion 13 of the hook is within the maximum allowable width of the hook proper which is preferably from 55 22 to 24 mils.

Slidably mounted on the threader-supporting shank or bar 6 is a threader-guard in the form of a casing comprising two separable sheet-metal half-sections 14^a and 15^a held together by a screw 16 which passes through the slot 17 in the threader-supporting shank 6. The section 14^a of the guard is formed with an inwardly struck tongue 18 which enters the slot 17 and is engaged by one end of a coil-spring 19 the other end of which is gripped by the inwardly extending ribs 20.

The guard sections 14^a and 15^a are formed near their free ends with contacting faces 21 in which are formed the registering guiding or steadyng grooves 22, Figs. 7 and 9, for the shank 9 of the threader wire. Beyond the contacting faces 21 the guard sections are formed with fingers 23 which are spaced apart sufficiently to clear the wire 9, as shown in Fig. 10. The fingers 23 diverge at their free ends and constitute a needle-contacting and centering mouth 24, Fig. 3.

It will be seen from Figs. 1, 2 and 3 that the threader-hook 12, as well as its shank 9, normally lies in a protected position within the guard-member 14^a, 15^a which slides freely on the supporting shank 6 and is yieldingly urged to hook-protecting position by the spring 19. The guard-section 14^a is formed with a clearance depression 25 for the end of the screw 11 and the inner end 26 of such depression is engaged by the screw 11 and constitutes a stop for limiting the outward movement of the guard 14^a, 15^a under the influence of the spring 19. The guard-sections are formed with guide-lips 27 which slidably engage the top and bottom edges of the threader-supporting shank 6 and one of these lips is extended at 27' beyond the face of the opposed guard section to constitute a thumb-catch facilitating the opening of the threader from its closed position shown in dotted lines in Fig. 1.

To use the device it should be held horizontally and the flared mouth 24 of the guard applied to the blade of the needle 28 close to the needle-eye 29. By applying a light endwise pressure to handle 4, while moving the latter up or down, the threader-hook 12 will be felt to enter the eye of the needle through which it is then projected to the position shown in Fig. 10 by a further gentle endwise movement of the handle 4. The thread 30 is then passed to the rear of the threader-hook 12 and is brought forwardly and upwardly under the hook-shank and then preferably passed laterally of itself through the throat 15^x and into the hook-cavity 15^c, as shown in dotted lines, Fig. 10. The thread-end should then preferably be released and the threader lifted slightly as its threaded hook is drawn through the needle-eye. By virtue of the provision of the narrow throat 15^x there is no danger that the thread will, after being released, slip laterally of itself out of the hook prior to withdrawal of the hook from the eye of the needle.

During the passage of the thread 30 through the restricted throat 15^x, the thread may be squeezed somewhat by its contact with the opposed walls of the throat. Also, the throat may be momentarily sprung open by the pressure of the thread passing therethrough; the nose 14 returning to its normal or unsprung position, Fig. 11, after the hook is threaded. The hook-cavity 15^c is large enough to receive a conventional sewing machine thread and permit the thread to

reeve freely lengthwise of itself through said cavity as the hook is withdrawn from the needle 28.

The return bend 13 at the end of the hook wire forms a smooth outwardly flaring mouth for reception of the sliding thread 30 in its movement from full line to dotted line position, Fig. 10. Also the blunt rounded nose 14 formed by such bend is not apt to catch upon the needle-eye and slips readily into and through such eye in the withdrawal movement of the hook.

In the modified form of hook shown in Fig. 12, the shank 9' is bent upon itself at its free end to form the open hook 12' and the free end 13' of the hook-forming portion 12' of the wire is bent inwardly upon itself to form the rounded blunt nose 14' at the outwardly flaring, smooth, thread-receiving mouth 15' leading through the restricted throat 15'' to the hook-cavity 15^a.

It will be observed that the bent positioning portion 10 of the threader wire lies in the same vertical plane with the hook 12. Consequently, when the positioning portion 10 is clamped against the vertical face 7 of the supporting shank 6 by the screw 11, the hook 12 is thereby correctly positioned in a plane parallel to the plane of the face 7.

Having thus set forth the nature of the invention, what I claim herein is:—

1. A needle-threader comprising a piece of spring wire of uniform cross-section bent at one end to form a resilient thread-hook small enough to freely enter the eye of a conventional sewing machine needle, the free end of the wire being bent back upon the bent hook-forming portion of the wire to form a rounded nose defining with the adjacent shank-portion of the hook a flaring thread-receiving mouth and a restricted throat, which latter is narrower than the normal unsqueezed diameter of a conventional sewing machine thread.

2. A needle-threader having a supporting element and a threader wire carried thereby and projecting therefrom, said wire being bent adjacent its free end to form a hook having a thread-receiving cavity, the extreme free end of the wire being bent back upon the bent hook-forming portion of the wire to form a rounded nose defining with the adjacent shank-portion of the hook a restricted throat narrower than said cavity and an outwardly flaring thread-receiving mouth.

3. A needle-threader having a supporting bar formed with a slot extending longitudinally thereof, a handle attached to one end of said bar, a resilient wire thread hook detachably mounted on the other end of said bar, a guard for said hook slidably mounted on and encasing said bar, said guard having an inwardly struck tongue entering said slot, and a spring disposed in said slot and acting upon said tongue to urge said guard to a position covering said hook.

4. A needle-threader comprising a piece of spring wire bent at one end to form a hook small enough to freely enter the eye of a conventional sewing machine needle, the free end of the wire being bent back upon the bent hook-forming portion of the wire to form a rounded nose defining with the adjacent shank-portion of the hook a flaring thread-receiving mouth.
